SUPPLEMENTAL LINING

Eloise T. Roe, Pleasantville, N. Y.

Application November 20, 1948, Serial No. 61,289

3 Claims. (Cl. 2—97)

1

This invention relates to a supplemental lining for garments.

The conventional coat or top coat for men, women and children is adapted for use only in the weather or season for which it is designed, for example, for spring or fall. In unseasonable, or extremely cold spring or fall weather, a different and heavier coat must be used, or warmer clothing worn underneath to maintain the desired body temperature.

And further, upon the onset of winter, a heavier coat must be worn, necessitating a coat wardrobe which is beyond the budget of many. Additionally, there are wide variations in winter weather, and even winter coats are designed for extremes in cold weather. For example, coats lined with alpaca pile have become popular for very cold weather. This lining material is characterized by its lightness, warmth retaining and insulating qualities. Another lining material, a patented fabric sold under the trade mark "Sunbak," is a lining having a smooth face and warmth retaining wool back which is used in many types of garments. This lining enhances the beauty of the coat and provides in one thickness of material both a lining and an interlining. Fur is also employed as a lining, as are other suitable materials, for instance, suede.

Various kinds of coats are currently made and sold, which are provided with detachable and separable linings, for adapting the coat to varying temperature changes, but heretofore there has not been provided a unitary lining ensemble having means which can be sewn or otherwise attached to a coat with the said supplementary lining used thereafter and detached at will.

It is an object of the invention to provide a unitary, supplementary lining having means for facile separable attachment to any coat, to adapt the coat to colder weather than that for which it was originally designed. It is another principal object to provide a lining having means for separable attachment to a plurality of coats, if desired. Another object is the provision of a coat lining which may be made of a wide range of materials, for example, wool back satin, called "Sunbak," alpaca pile, wool, or fur, so that the user may interchange linings at will in different coats as the weather changes. Thus for a minimum of expense, one is enabled to comfortably surmount various weather variations.

Further objects and advantages will be apparent from the disclosure in the drawings and description herein.

2

In the drawings:

Fig. 1 is a front view of the supplemental lining.

Fig. 2 illustrates a fragmentary view of the 5 slide fastener attachment.

Fig. 3 is a fragmentary enlarged view of the means for concealment of the slide fastener.

Fig. 4 is a sectional (enlarged) view along the 10 lines 4—4 of Fig. 1 showing the complete covering or concealment of the slide fastener between the outer garment and the supplementary lining.

The supplementary lining 10 comprises separable lining 11 best shown in Fig. 1, provided at its 15 outer marginal edges with conventional slide fastener having complementary slide fastener teeth elements 12, 13, gripping respectively, the slide fastener strips 14, 15 and having slider 16 for closing and opening the fastener and for 20 separating lining 11 from its cooperating parts. As depicted in Fig. 1, lining 11 is shaped to fit snugly within a coat, and has sleeves, but, if desired, the sleeves may be omitted.

Lining 11 is preferably turned under at its 25 edges and sewn or otherwise secured to strip 14 as at 17 and it is contemplated that said lining may be of any material which has, inherently, warmth retaining qualities. For example, the patented material sold under the trade mark 30 "Sunbak" is one material admirably suited. "Sunbak," as hereinbefore stated, has the smooth face of the conventional lining and a wool back, combined in one material. Other materials may be alpaca pile, for extremely cold weather, wool, 35 or any fabric made entirely or in part of natural or artificial fibers which insulate, but preferably, do not add any considerable weight. Fur, suede, or leather may also be used.

An important feature of the present invention 40 lies in the provision of flap 18, suitably attached as at 19, by sewing to strip 15, said flap having a dual purpose. First, it is a means of securing the strip 15 and fastener element 13 to the lining of the coat to be converted and second, it covers 45 the fastener elements 12, 13 and strips 14, 15 when lining 11 is attached to the coat, and covers element 13 and strip 15 when lining 11 is detached. As admirably shown in Fig. 4 flap 18 is adapted to be attached to the material 20 of the 50 coat to be converted, so that the said flap covers the cooperating members of the slide fastener and their adjacent strips.

It is contemplated that removable white thread or dot and dash marking 21 may be provided 55 along flap 18, along which directional line the

3

flap may be sewn to the material of the coat (not shown) to be modified.

Flap 18 preferably assumes the form of a ribbon member as disclosed in Figs. 3 and 4 or it may be of double thickness, (not shown) as desired.

Supplementary lining 10 may be provided with a plurality of outer fastener elements 13, strips 15 and flaps 18 so that the flaps may be sewn or affixed to the linings of several coats and lining 10 used with any one of the modified coats when desired.

I propose that supplementary lining 10 shall be manufactured and sold as a unit, with at least one complete slide fastener slider and covering flap, or a plurality, as described in the paragraph above. Thus, for the nominal cost of one extra lining, several coats of the wardrobe may be converted or expeditiously modified for colder weather.

The slide fastener teeth elements are shown terminating short of the bottom of lining 11, for I have found that the lining when made this way does not rumple. If desired, however, the slide fastener may be extended all the way to the bottom.

Any coat of a wardrobe, whether long or short, suitcoat or topcoat for spring, fall or winter may be converted or modified by employing my supplementary lining.

It is merely necessary to sew flap 18 to the material of the coat to be converted, along the thread or marking 21 and lining 11 may thereafter be inserted or removed with despatch, making the modified coat comfortable to wear in 35 colder weather than that for which the garment was originally designed.

The supplementary lining can be manufactured at nominal cost, from readily available materials, and can be made and sold at a figure 40 within the budget of many who could not otherwise afford a coat designed to be comfortable in really cold weather.

The above disclosure should be understood as illustrative only and not by way of limitation since changes may be made without departing from the spirit of the invention. The material may be changed; buttons or fastening means other than a slide fastener may be employed; means other than sewing may be used.

4

The right is reserved to make such changes or modifications as may come within the scope of the appended claims.

I claim:

1. A supplemental garment lining for converting a coat, comprising a lining provided at its outer marginal edges with complementary slide fastener parts and strips, one of said strips being attached to the lining, the other strip carrying a flap provided with markings whereby upon application of the lining to a coat to be converted, said markings may be followed to sew the lining to a coat.

2. A supplemental garment lining for converting a coat, comprising a lining provided at its outer marginal edges with complementary slide fastener parts with attached strips, one of said strips sewn to the said lining, the other strip sewn to a flap provided with a directional marking spaced from and along one marginal edge of said flap whereby upon application of the lining to a coat, the lining may be sewn thereto along the directional marking.

3. A supplemental garment lining for converting a garment, comprising a lining with warmth retaining qualities provided at its outer marginal edges with complementary slide fastener parts with attached strips, one of said strips sewn to the said lining, the other strip sewn to the outside of a single thickness of material in the form of an elongated flap of the same length as the complementary slide fastener parts, the elongated flap provided with directional marking along one marginal edge thereof whereby the flap may be sewn to the material of the inside of a coat along said directional marking with the inside of the single thickness of material contiguous the material of the inside of the coat.

ELOISE T. ROE.
